ELEVATOR CAR CONSTRUCTION

Louis C. Musilli, Detroit, Mich.

Application July 31, 1950, Serial No. 176,840

7 Claims. (Cl. 214—512)

1

This invention relates to elevator cars and refers more particularly to improvements in elevator cars employed for industrial use.

It is an object of this invention to provide an elevator car with a load supporting floor which is movable from one side of the car to the other to enable readily shifting the load. In accordance with this invention the floor of the car is actually in the form of a flexible endless belt capable of being driven in opposite directions to shift the load supported thereby to different positions in the car without actually handling the load.

The foregoing as well as other objects will be made more apparent as this description proceeds, especially when considered in connection with the accompanying drawings, wherein:

Figure 1 is a semi-diagrammatic view of an elevator car embodying the features of this invention;

Figure 2 is a sectional view through the car shown in Figure 1;

Figure 3 is a fragmentary plan view partly in section of a part of the car shown in Figure 1;

Figure 4 is a sectional view taken on the line 4—4 of Figure 3;

Figure 5 is an elevational view partly in section of a part of the elevator car construction;

Figure 6 is a fragmentary perspective view of the construction shown in Figure 5;

Figure 7 is a diagrammatic plan view of the elevator car; and

Figure 8 is a fragmentary perspective view showing a part of the door construction for the car.

The elevator car is indicated generally in Figure 1 of the drawings by the numeral 10 and forms a unit in itself. The arrangement is such that the car may be operated in a shaft located within the building structure, or may also be operated within an auxiliary shaft which is erected exteriorly of a building. In any case the elevator car is provided with a rigid rectangularly shaped horizontal frame structure 11 and a vertical frame structure 12. The two frames are formed of steel bars of any suitable cross sectional contour, and are rigidly secured together by welding or some equivalent method to form a unitary assembly.

The front side of the elevator car is indicated generally by the numeral 13, and the rear side is designated by the numeral 14. As shown particularly in Figure 1, the front side 13 is divided into two openings 15 and 16 by a division bar 17 of the vertical frame structure. The

2

opening 13 is normally closed by a sectional door 17 and the opening 16 is closed by a similar door 18. Both doors are formed of a plurality of sections suitably hingedly connected together, in order to enable movement of the doors along the curved path of travel provided by channels 19. The channels 19 are shown in Figure 2 as having vertical sections 20 located at the front side 13 of the car and as having horizontal sections 21 extending inwardly at the top of the car. The two sections 20 and 21 are integrally connected by an arcuate section 22. In practice a channel 19 is provided at each side edge of the two doors and rollers 23 are supported at the side edges of the doors in positions to respectively engage with the channels 19. The arrangement is such as to permit the two doors to be independently moved to open and closed positions.

The rear side 14 of the elevator car is also divided into two separate openings, and these openings are independently closed by doors 24 and 25. The doors 24 and 25 are identical in construction to the doors 17 and 18, and are guided throughout their movements by channels 26 identical to the channels 19 previously described. Thus the doors at opposite sides of the elevator may be quickly moved independently of one another to open and closed positions.

The sides of the car 10 adjacent the sides 13 and 14 may be permanently closed by suitable side walls attached to the vertical frame structure 12, or may be open. In the present embodiment of the invention, the sides of the elevator car adjacent the sides 13 and 14 are open, and doors 27 of the overhead type are provided for closing these sides. The doors 27 are preferably identical in construction to the doors 17, 18, and are mounted in the same manner as the latter doors.

The elevator car 10 has a load supporting floor 30 which is movable between the side openings 13 and 14 in order to facilitate loading and unloading of the elevator car with a minimum amount of handling of the load. As shown in Figure 4 of the drawings the floor 30 comprises an endless belt 31 of flexible material which extends from the side opening 13 to the side opening 14, and is movable in opposite directions toward and away from these openings. The width of the belt approximates the width of the elevator car so that the top section 32 of the belt actually forms the complete floor for the elevator.

Referring again to Figure 4 of the drawings, it will be noted that the ends of the belt 31 are

reeved around drums 33 respectively journaled on the frame 11 adjacent the openings 13 and 14. Inasmuch as the belt is of a flexible nature, the top section 32 is supported throughout substantially its entire length by a multiplicity of rollers 34 having their axes extending parallel to the axes of the drums 33. The opposite ends of the rollers 34 are journaled on the frame structure 11 in such close relationship that the rollers cooperate to provide a substantially continuous support for the top section 32 of the belt 31.

The belt 31 is driven by a pair of driving drums 35 journaled on a rectangular subframe 36 suspended at the corners from the horizontal frame 11 by vertical hangers 37. As shown in Figure 3 of the drawings the drums 35 are secured to a common shaft 38 in axial spaced relationship, and the opposite ends of the shaft 38 are journaled on the frame 36 in a position to locate the driving drums 35 midway between the drums 33.

The driving drums 35 respectively cooperate with a pair of drums 39 to frictionally grip the bottom section of the belt 31 therebetween. The drums 39 extend between the top and bottom sections of the belt and are supported on the frame structure 11 for rotation about axes parallel to the axes of the drums 33. It is also pointed out that the drums 39 assist in supporting the top section 32 of the belt in a horizontal position. In order to maintain the belt in a taut condition, suitable idler rolls 40 are supported on the frame structure 11 in positions to respectively engage the bottom section of the belt between the drums 33 and 39.

In order to drive the drums 35 a pair of reversible electric motors 41 and 42 is provided. These motors are respectively supported on the subframe 36 at opposite sides of the drums, and are wired to rotate their drive shafts 43 in opposite directions. The drive shafts 43 are selectively coupled to driven shafts 44 through the medium of clutches 45 which may be of any suitable construction and are preferably of the type capable of being automatically operated from some remote point. In any case the inner ends of the shafts 44 have bevelled pinions 47 secured thereto, and these pinions mesh with a bevelled gear 48 secured to the shaft 38 intermediate adjacent ends of the driving drums 35.

In normal use only one motor is employed for driving the drums 35, and the other motor is held in reserve. However, in the event the load on the belt 31 is excessive, both motors may be employed for the purpose of driving the belt.

The subframe 36 is vertically adjustable relative to the frame 11 in order to vary the pressure applied to the belt by the driving drums 35. As shown in Figures 5 and 6, suitable brackets 50 are secured to the lower ends of the members 37 and are provided with vertically extending slots 51. The subframe 36 is provided with pins 52 at the corners which extend through the vertical slots 51 and are respectively engaged by wedges 53. The wedges 53 are slidably supported on the brackets 50 and are adjusted by suitable studs 54. The arrangement is such that rotation of the studs 54 in a direction to move the wedges 53 inwardly raises the subframe 36 and increases the pressure of engagement of the drums 35 with the bottom section of the belt 31.

It follows from the foregoing that the elevator car has a movable floor which not only facilitates loading and unloading of the car, but also enables shifting the load to different posi-

tions in the car with a minimum handling of the load. In addition it will be noted that the floor structure is very simple, and may be readily operated by suitable controls located at any convenient place within the car.

What I claim as my invention is:

1. An elevator car comprising a frame structure, a plurality of drums rotatably supported on said frame structure below the floor level of the car with the axes of said drums generally horizontal and mutually parallel, a flexible endless belt reeved over said drums with the top section of said belt providing a load supporting floor for the car, a plurality of rollers supported on said frame in juxtaposition with the axes thereof extending parallel to the axes of said drums and positioned between said drums in load supporting relation to the said top section of said belt, and means for driving said belt, 10 15 20 25 30 35

2. The elevator car set forth in claim 1 in which said driving drum is mounted on a vertically adjustable subframe supported by said frame structure, said subframe and frame structure being formed with portions having vertically elongated slots in the one respectively engaged by pins on the other, and cam means slidably supported by said slotted portions and respectively engageable with said pins to provide vertical adjustment of said subframe relative to said frame structure, thereby to vary the pressure applied to said belt by said driving drum.

3. An elevator car comprising a frame structure having side enclosing walls, a plurality of drums rotatably supported on said frame structure below the floor level of the car with the axes of said drums generally horizontal and mutually parallel, a flexible endless belt reeved over said drums with the top section of said belt providing a load supporting floor for the car, a plurality of rollers supported on said frame in juxtaposition with the axes thereof extending parallel to the axes of said drums and positioned between said drums in load supporting relation to the said top section of said belt, and means for driving said belt in opposite directions, said drums and rollers extending from one side wall of the car to the other, said belt occupying substantially the entire area defined by the side walls of the car, and at least one of the walls adjacent the ends of the path of travel of said belt being movable to open position to expose said belt for loading and unloading.

4. An elevator car comprising a frame structure having side enclosing walls, a plurality of rolls rotatably supported on said frame structure in juxtaposition below the floor level of the car with the axes of said rolls generally horizontal and mutually parallel, a flexible endless belt reeved over said rolls with the top section of said belt providing a load supporting floor for the car, and means for driving said belt, said rolls extending from one side wall of the car to the other, said belt occupying substantially the entire area defined by the side walls of the car, and at least one of the walls adjacent the ends of the path of travel of said belt being movable to open position to expose said belt for loading and unloading.

5. An elevator car comprising a frame structure, a plurality of rolls rotatably supported on said frame structure in juxtaposition below the floor level of the car with the axes of said rolls generally horizontal and mutually parallel, a flexible endless belt reeved over said rolls with the top section of said belt providing a load supporting floor for the car, and means for driving said belt, said belt driving means comprising a prime mover, and a driving drum located below the bottom section of said belt in frictional contact with said bottom section, at least one of said rolls cooperating with said driving drum to frictionally clamp the adjacent portion of said belt therebetween.

10 15 20 25 6. An elevator car comprising a frame structure having side enclosing walls, load supporting floor structure comprising a plurality of rolls rotatably supported on said frame structure below the floor level of the car with their axes generally horizontal and mutually parallel, said rolls being arranged at spaced intervals from one side wall to the opposite side wall, a flexible endless belt reeved over said rolls with the top section of said belt providing a load supporting floor for the car, and means for driving said belt in opposite directions, said belt occupying a major portion of the area defined by said side walls, and at least one of said side walls adjacent the ends of the

path of travel of said belt being movable to open position to expose said belt for loading and unloading.

7. An elevator car as defined in claim 6 in which both of the opposite side walls adjacent the ends of the path of travel of said belt are movable to open position to expose said belt for loading and unloading.
